UNITED STATES PATENT OFFICE.

JOHN F. WELSH, JR., OF SHERIDAN, WYOMING.

DESIGN FOR A CANDLE.

Application filed May 10, 1922. Serial No. 2,169. Term of patent 7 years.

To all whom it may concern:

Be it known that I, JOHN F. WELSH, Jr., a citizen of the United States, residing at Sheridan, in the county of Sheridan and State of Wyoming, have invented a new, original, and ornamental Design for a Candle, of which the following is a specification, reference being had to the accompanying drawing, forming part thereof, and in which—

I claim:

The ornamental design for a candle, as shown.

JOHN F. WELSH, Jr.
